UNITED STATES PATENT OFFICE.

DANIEL SCHUYLER, OF NEW YORK, N. Y.

MUSIC-CABINET.

SPECIFICATION forming part of Letters Patent No. 289,570, dated December 4, 1883.

Application filed August 7, 1883. (No model.)

To all whom it may concern:

Be it known that I, DANIEL SCHUYLER, of the city, county, and State of New York, have invented certain new and useful Improvements 5 in Music-Cabinets, of which the following is a specification.

This invention has reference to certain improvements in the music-cabinet for which Letters Patent have been filed by me under 10 date of April 5, 1883, and Serial No. 90,756, whereby a simpler form of cabinet, that can also be used as a file for newspapers, writing-paper, and the like, is obtained; and the invention consists of a casing that is open at the 15 front, and provided with a rack hinged to the bottom of the same, said rack having a weighted and inclined bottom. The rack is retained in an open horizontal position by fixed bottom hooks engaging stop-pins of the 20 side walls of the casing, and in a vertical position by a button and a spring-catch near the lower part of the rear wall of the casing.

In the accompanying drawings, Figure 1 represents a front elevation, and Figs. 2 and 25 3 are vertical transverse sections of my improved music-cabinet, showing the same, respectively, in closed and open position.

Similar letters of reference indicate corresponding parts.

30 A in the drawings represents the casing of my improved music-cabinet, which casing is made of any suitable material, size, and finish, and which is attached to the wall by hooks, screws, or other fastening devices, that are 35 passed through holes in the back of the casing A. The casing A is open at the front, and provided with a rack, B, that is hinged to the bottom A' of the casing A. The rack B has a bottom, B', with an upwardly-extending inner strip or flange and partly or entirely closed sides. The upper surface of the bottom B' is inclined toward the front panel of the rack, so as to throw the upper sheets of music slightly forward, and facilitate thereby 40 their removal from the rack. The bottom B' is made of sufficient thickness, so that its weight overcomes the weight of the front panel of the rack, and causes thereby the return of the same into vertical position when it has been 45 lifted far enough so that its center of gravity passes over the rack-hinges to the interior of the casing. The bottom B' of the rack may

also be leaded, so as to increase its weight. Stop-hooks b are applied to the sides of the rack B, and adapted to engage fixed stop-pins b' of the side walls of the casing A, the side walls being set back sufficiently to pass along the stop-pins, or provided with grooves, so as to move along the stop-pins.

In place of using a rack having weighted 60 or leaded bottom, the stop-pins may be made of sufficient size to produce the counter-balancing of the front panel of the rack, and return the same into upright position when the same has been lifted far enough. The 65 bottom A' of the casing A is provided with recesses b'', into which the stop-hooks enter when the rack is in its vertical position. A stop-pin, d, at the upper part of one or both side walls of the casing A serves to stop the 70 rack when it arrives in upright position, and prevents the abutting of the rack-bottom against the rear wall of the casing A. A button, e, that is attached to the rear part of the rack-bottom B', is engaged by a spring, e', at 75 the lower part of the rear wall of the casing A, said spring e' exerting sufficient friction on the button e to retain the front rack until a sufficient forward pressure is exerted upon the panel of the same, so that the button is 80 released from the spring. By arranging the retaining-spring near the bottom of the casing A, it is entirely hid by the rack, whether the same is in open or closed position.

The cabinet can be manufactured cheaply, 85 and forms a neat and convenient device for storing away music and other articles.

Having thus described my invention, I claim as new and desire to secure by Letters Patent—

1. A music-cabinet consisting of a casing 90 open at the front, and a rack hinged to the front edge of the bottom of the same, and means, substantially as described, whereby the rack is retained in a horizontal or upright position, substantially as set forth.

2. The combination of a casing, A, open at the front, a rack, B, having a weighted bottom, B', and being hinged to the bottom of the casing A, hooks b b', attached to the rack, and stop-pins b' b'', attached to the side walls 100 of the casing, substantially as set forth.

3. The combination of a casing, A, open at the front, a rack, B, that is hinged to the bottom of the casing and provided with a weighted

bottom, hooks *b b*, attached to the rack, stoppins *b' b'*, attached to the side walls of the casing, a button, *e*, at the rear wall of the bottom of the rack, and a retaining-spring, *e'*, applied to the rear wall of the casing, substantially as specified.

In testimony that I claim the foregoing as

my invention I have signed my name in presence of two subscribing witnesses.

DANIEL SCHUYLER.
